Des. 177,619
Patented May 8, 1956

177,619

TOILET PAPER HOLDER OR SIMILAR ARTICLE

Mary Ellen Floherty, Northport, N. Y.

Application April 29, 1955, Serial No. 35,747

Term of patent 14 years

(Cl. D4—3)

The drawing shows a frontal perspective view of a toilet paper holder or similar article embodying my new design.

The roll of toilet paper and roller disclosed by means of broken lines are shown only for purposes of illustration.

I claim:

The ornamental design for a toilet paper holder or similar article, substantially as shown and described.
